US00D802647S

(12) **United States Design Patent** (10) Patent No.: **US D802,647 S**
(45) Date of Patent: **** Nov. 14, 2017**

(54) **CAMERA STAND**(71) Applicant: **GOOGLE INC.**, Mountain View, CA (US)(72) Inventors: **Gregory R. Duffy**, San Francisco, CA (US); **Melissa D. McLean**, Novato, CA (US); **Aamir S. Virani**, San Francisco, CA (US)(73) Assignee: **GOOGLE INC.**, Mountain View, CA (US)(**) Term: **15 Years**(21) Appl. No.: **29/549,995**(22) Filed: **Dec. 29, 2015****Related U.S. Application Data**

(63) Continuation of application No. 14/701,283, filed on Apr. 30, 2015, which is a continuation of application No. 13/604,399, filed on Sep. 5, 2012, now Pat. No. 9,071,740.

(51) **LOC (10) Cl. 16-05**(52) **U.S. Cl.**USPC ..... **D16/219**(58) **Field of Classification Search**USPC D16/200, 202-205, 208, 218, 219, 242; 348/14.01-14.06, 143, 146, 148, 208.11, 348/373-376; 396/427, 535, 539-541

CLAIM

The ornamental design for a camera stand, as shown and described.

DESCRIPTION

The present application is also related to U.S. patent application Ser. No. 29/549,992, filed on Dec. 29, 2015, titled “A Video Camera,” and U.S. patent Application Ser. No. 29/549,999, filed on Dec. 29, 2015, titled “An Assembly,” each of which is hereby incorporated by reference in its entirety.

FIG. 1 shows a front perspective view of a camera stand showing our new design with a camera module in broken lines to illustrate an environment.

FIG. 2 shows a front elevation view of the camera stand shown in FIG. 1.

FIG. 3 shows a rear elevation view of the camera stand shown in FIG. 1.

FIG. 4 shows a left side view of the camera stand shown in FIG. 1.

FIG. 5 shows a top plan view of the camera stand shown in FIG. 1.

FIG. 6 shows a bottom plan view of the camera stand shown in FIG. 1.

FIG. 7 shows a front perspective view of a camera stand, shown with a camera module and a base disclosed in broken lines to illustrate an environment.

FIG. 8 shows a front elevation view of the camera stand shown in FIG. 7.

FIG. 9 shows a rear elevation view of the camera stand shown in FIG. 7.

FIG. 10 shows a left side view of the camera stand shown in FIG. 7.

FIG. 11 shows a top plan view of the camera stand shown in FIG. 7; and,

FIG. 12 shows a bottom plan view of the camera stand shown in FIG. 7.

The broken lines in the drawings are included for the purpose of illustrating environmental subject matter that form no part of the claimed design.
